(57) **CLAIM**

I claim the ornamental design for tool pouch having drain, as shown.

DESCRIPTION

FIG. 1 is a perspective view of a tool pouch having a drain showing my new design;

FIG. 2 is a front elevation view thereof;

FIG. 3 is a rear elevation view thereof;

FIG. 4 is a bottom plan view thereof;

FIG. 5 is a top plan view thereof;

FIG. 6 is a side elevation view thereof;

FIG. 7 is a second side elevation view thereof; and,

FIG. 8 is an enlarged perspective view of the drain shown in FIG. 1.
